UNITED STATES PATENT OFFICE.

EDWARD JOHN RIDGWAY, OF HEMPSTEAD, NEW YORK, ASSIGNOR TO MEAKIN & RIDGWAY, INC., OF NEW YORK, N. Y., A CORPORATION OF NEW YORK.

DESIGN FOR A COVERED DISH OR SIMILAR ARTICLE.

Application filed August 15, 1928. Serial No. 27,821. Term of patent 14 years.

To all whom it may concern:

Be it known that I, EDWARD JOHN RIDGWAY, a subject of the King of Great Britain and Ireland, residing at Hempstead, Long Island, in the county of Nassau, State of New York, have invented a new, original, and ornamental Design for Covered Dish, of which the following is a specification, reference being had to the accompanying drawing, forming part thereof.

I claim:

The ornamental design for a covered dish or similar article, as shown.

In testimony whereof I have signed by name to this specification.

EDWARD JOHN RIDGWAY.
